(No Model.)

J. W. POST.

STATION INDICATOR.

No. 370,410.

Patented Sept. 27, 1887.

UNITED STATES PATENT OFFICE.

JOHN W. POST, OF NEW YORK, N. Y.

STATION-INDICATOR.

SPECIFICATION forming part of Letters Patent No. 370,410, dated September 27, 1887.

Application filed January 7, 1887. Serial No. 223,657. (No model.)

To all whom it may concern:

Be it known that I, JOHN W. POST, a citizen of the United States, residing at New York, in the county of New York and State of New York, have invented certain new and useful 5 Improvements in Station-Indicators; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 This invention relates to improvements in that class of devices used upon passenger-cars to indicate the approach of the train to a station, and which are known as "station-indicators," and are intended to give notice to the 20 occupants of a car of their approach to a station long enough before the train reaches it to enable them to gather their wraps and hand-baggage, and be ready to leave the car when the train stops, thus avoiding the trouble experienced by travelers in ascertaining the station at which they wish to leave the train from the indistinct calls of the brakeman. 25 Many plans have been devised for the construction of these indicators; but, so far as my knowledge extends, they have failed to come into general use.

The object of this invention is, therefore, to 30 simplify and improve the construction and method of operating these indicators as to make them a desirable part of the equipment of every passenger-car.

This station-indicator consists, essentially, 35 of a series of rectangular frames or tablets having the names thereon, in large letters, of the several stations along the line upon which the car provided with the station-indicator runs. These indicating-tablets are provided with 40 eyes, through which pass rods attached to the car, and so arranged as to allow the tablets to be placed either in a horizontal or vertical position. When in a vertical position, one side of the tablet is exposed to the view of the people in the car, and bears an inscription giving the name of the next station at which 45 the train will stop. It is evident that the passengers will take notice of this, and be ready to leave as soon as the train comes to a stand, thus avoiding the delay that often occurs from their inability to get ready to leave on so short

a notice as is now ordinarily given. When 55 the tablets are not in use for the purpose of indicating stations, they are turned up into a horizontal position, and present only an edge view to the eyes of the passengers.

To fully understand the method of operating 60 this apparatus, I will now describe its construction in detail.

In the accompanying drawings, in which the same letters of reference indicate like parts in the different figures, Figure 1 is a perspective 65 view of the indicating apparatus attached to the end of a car above the entrance-door. Fig. 2 is a vertical section of one end of the car, showing the construction and operating devices of the indicator. Fig. 3 shows one of 70 the tablets separately. Fig. 4 shows a modification of the tablet, in which the eyes for the passage of the supporting-rods are attached to instead of being formed in the tablet, as in the preceding figure. Fig. 5 shows the operating- 75 key, by means of which the train-men control the movement of the tablets.

In these figures, A represents the end of a passenger-car, and B a car-door.

In a suitable position above the door is secured to the end of the car, by screws or other proper devices, a bed-plate, C, which carries the indicating apparatus, consisting of the rods or bars D D, each of which is secured at one end to the bed-plate, as shown, and having a horizontally-projecting portion, a, a vertical portion, a', and a horizontal part, a'', at right angles to the part a. They are again bent at right angles to the part a'' to form the part b, after which they are bent again to a 90 right angle, forming the downwardly-extending parts b', which are close together and carry the fulcrum-pin i, upon which the catch-lever E oscillates.

The tablets F are formed of any suitable 95 material and have eyes e e near one edge, as shown in Fig. 3; or these eyes may be attached to the tablets, as illustrated in Fig. 4. Each tablet has the name of a station painted or otherwise placed thereon, and is attached to the rods D by means of the eyes e, through which the rods pass, as shown in Fig. 1 of the drawings, where a part of the tablets are arranged in a vertical and the remainder in a horizontal position. The edge of each tablet opposite 100 the eyes is preferably chamfered, so that it may readily enter the notch c on the lower 105 end of the catch-lever, so that when said tab-

lets are in a horizontal position, the lower one of the pile will be held in that position by the catch-lever at one side and the part *a* of the rods *D* at the other, and of course all the 5 other horizontal tablets in the pile will be supported by this lower one.

To the upper end of the catch-lever *E* is attached a cord, *d*, which passes over a small pulley, *h*, placed in the end of the car. From this 10 pulley the cord passes downward between the outer and inner portions of the car end through the door-space left between them to a suitable spool or reel, *k*, journaled in sockets *m*, secured in said outer and inner portions of the car- 15 covering. Each end of this reel *k* within the socket *m* is squared to fit the squared hole or socket in the key *G*, by means of which key the reel is turned to wind up the cord and thus draw the upper end of the catch-lever toward 20 the end of the car, which movement of said lever releases the edge of the lower tablet in the horizontal pile and allows it to drop into a vertical position, exposing the name of the station thereon to the view of the occupants of 25 the car. A spring, *n*, secured to the part *b* of the rods *D*, bears against the inner side of the catch-lever and forces it into position to engage with the next lower tablet in the horizontal pile as soon as the key is released or 30 moved from the reel.

It will be seen that the operating-cord is entirely out of danger of being interfered with by the passengers or other unauthorized individuals, as the only part of it exposed within 35 the car is wholly above the reach of a person standing on the car-floor, and even this part of said cord may, if desired, be carried in a covered way just beneath the roof. If the door of the car should not be a sliding one, thus 40 leaving no space between the outer and inner coverings of the car, the cord may be carried down to the reel in a covered way upon either the outer or inner side of the car, the object in concealing it being to prevent any but authorized persons provided with a key from 45 changing the tablets, so that no mistakes in announcing the stations may occur.

It will be apparent that other methods of operating the tablets might be devised. For 50 instance, the lower end might be provided with a ring or with a tuft, like a bell-pull; but these devices would be open to the objections that they might be operated by any person. I therefore prefer the reel and key hereinbefore described, or their equivalents, for this 55 purpose.

The method of operating this station-indicator is as follows: Before the car leaves its starting-point the tablets are all placed in a 60 horizontal position, supported at one side by the catch-lever and at the other by the lower horizontal portion of the rods *D*, the series of tablets being so arranged that the one bearing the name of the first station to be reached 65 after starting shall be at the bottom of the pile, the one bearing the name of the second station immediately above it, and so on in regular

order until the tablet bearing the name of the last station is reached, which is at the top of the pile. After starting and before reaching 70 the first station, a brakeman or other train-hand, by means of the key, turns the reel and releases the lower tablet, which drops in a pendent position upon the lower horizontal part of the rods *D*, in which position it remains 75 until the station it indicates has been passed, when the next tablet is released and falls in front of the one preceding it, hiding it from the view of the passengers, and giving in its place the name of the next station. 80

It will be seen that these tablets are adapted to be dropped by turning the reel, and that this may be done by an operator either within the car or out upon the platform, so that it is not necessary for a brakeman to leave his position upon the platform in order to notify the passengers of the name of the next station at which the train will stop. 85

I am aware that a station-indicator provided with a series of tablets having the names of 90 railway-stations upon one side and an advertisement upon the other and arranged upon supporting-bars in such a manner that when turned up above said bars the side of the tablet having the name of the station thereon 95 shall be exposed to the view of the passengers in the car, and when said tablets are turned down the opposite side, bearing an advertisement, shall be presented to their view, and that devices arranged to allow these tablets to 100 fall in succession and adapted to be operated by the train-men, have been invented, as shown in United States Patent No. 188,915. I do not, therefore, broadly claim such devices, but limit my claims to the construction of the 105 apparatus, as hereinafter stated.

Having thus described my invention, I claim as new and desire to secure by Letters Patent the following:

1. In a passenger-car station-indicator, the 110 combination of the tablets adapted to be supported in either a horizontal or vertical position, the catch-lever fulcrumed on the tablet-supports, a spring acting on said lever, the cord concealed in the car end, the reel upon 115 which said cord winds, and the operating-key, arranged as shown and described to operate said tablets, for the purpose specified.

2. In a passenger-car station-indicator, the operating-cord attached to the catch-lever, 120 by which the tablets are retained in a horizontal position, in combination with the reel placed in the car end and sockets forming journals for said reel secured to the inner and outer sides of the car, said sockets adapted to 125 receive the key which turns the reel from either the platform or inside of the car, as may be desired.

In testimony whereof I affix my signature in presence of two witnesses.

JOHN W. POST.
